UNITED STATES PATENT OFFICE.

FRANK L. GORMLEY, OF BROOKLINE, MASSACHUSETTS, ASSIGNOR TO A. O. NORTON,
INC., OF BOSTON, MASSACHUSETTS, A CORPORATION OF MAINE.

SELF-LOWERING HIGH-SPEED LIFTING JACK.

Application filed October 26, 1921. Serial No. 510,537.

To all whom it may concern:

Be it known that I, FRANK L. GORMLEY, a citizen of the United States of America, and a resident of Brookline, in the county of 5 Norfolk and State of Massachusetts, have invented certain new and useful Improvements in Self-Lowering High-Speed Lifting Jacks, of which the following is a specification.

10 This invention relates to high speed lifting jacks and is an improvement on the invention shown and described in U. S. Patent No. 1,329,665 issued Feb. 3, 1920, to J. C. Kopf and F. H. Schwerin.

15 It is also an improvement upon the invention shown and described in U. S. Patent No. 1,288,210 issued May 29, 1917, to I. E. Hindman.

The main object of the present invention 20 is to provide jacks, constructed similar to either of the jacks shown in the patents above referred to, with means whereby the speed of the jack when lowering under its load, may be controlled instead of necessitating the use of a crank to lower the load.

By means of the improvements herein shown and described, the jacks of the patentees will become self-lowering jacks.

The invention consists in certain novel 30 features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the 40 invention consists can be variously arranged and organized and the invention is not limited to the precise arrangement and organization of these instrumentalities as herein shown and described except as required by 45 the scope of the appended claims.

Of the drawings:

Figure 1 represents a vertical section embodying the principles of the present invention.

50 Figure 2 represents a vertical section of the same on line 2, 2, on Fig. 1.

Figure 3 represents a horizontal section of same on line 3, 3, on Fig. 2, and

55 Figure 4 represents a horizontal section on line 4, 4, on Fig. 2.

Similar characters indicate like parts throughout the several figures of the drawings.

In the drawings, 10 is the base of a lifting jack having the upwardly extending cylindrical standard 11 provided with bearing surfaces 12 for the cylindrical ram 13 adapted to be moved vertically relatively to said standard 11.

The upper end of the ram 13 has secured thereto a head 14 and in the lower end of said ram is fixedly secured a nut 15.

Extending through the nut 15 is a rotatable screw 16 having a steep pitch helical thread.

The lower end of the screw 16 has secured thereto a plate 17 resting on antifriction members 18 supported by a fixed plate 19 mounted in the base 10.

Above the plate 17 and keyed to the screw 75 16 is a gear 20 which meshes with a pinion 21 keyed to the shaft 22 parallel with the screw 16 and having its opposite ends mounted in bearings 23 and 24 within an annex section 25 secured to one side of the casing 80 10, 11, by bolts 26.

The shaft 22 has also keyed or otherwise secured thereto, a bevel gear 27 meshing with a bevel pinion 28 rotatable with the lifting shaft 29 extending laterally from 85 the annex section 25.

This lifting shaft 29 has a bearing in the gland 30 and its outer end is flat-sided, as at 31, to receive the usual operating mechanism which may be of any well-known 90 construction.

Midway of the shaft 22 is a bearing 32 therefor and above this bearing said shaft has keyed or otherwise secured thereto the ratchet 33.

Above said ratchet 33 and loosely mounted on the vertical shaft 22 is a gear 34 having a downwardly extending flange 35 in which are mounted the pawls 36 pivoted at 37 and forced into engagement with the teeth of the ratchet 33 by suitable springs 36.

As thus far described, the construction is substantially identical with that shown and described in the before-mentioned Patent 105 No. 1,329,665.

A pinion 38 meshes with the gear 34, this pinion preferably being formed integral with a worm gear 39, the teeth of which mesh with the worm 40 secured to one end 110

of and revoluble with the shaft 41 mounted in bearings 42 and 43 formed in the annex section 25.

The opposite end of the shaft 41 has secured thereto a gear 44 meshing with a pinion 45 mounted on a short shaft 46 freely revoluble in a bearing 47 and having secured to its opposite end a gear 48.

The teeth of the gear 48 mesh with those 10 on a gear 49 on the shaft 50 of the brake wheel 51.

Pivoted at 52, 52 are curved brake arms 53 which partially surround the brake wheel 51.

15 Normally these brake arms 53 are in sufficient frictional contact with the brake wheel 51 as to prevent the rotation of said brake wheel 51.

The opposite ends of the brake arms 53 20 are forced toward each other by springs 54 interposed between the outer faces of said arms 53 and ears 55 on the annex section 25.

Interposed between the free ends of said arms 53 is a pivoted cam block 56 having 25 flattened sides, this block being normally in the position indicated in Fig. 1 of the drawings.

The cam block 56 has secured to its shank, an operating handle 57, by manipulating 30 which the arms 53 may be separated from the brake wheel 51 to permit the free rotation of said brake wheel.

When it is desired to lift a load upon the head 14, an operating device is placed upon 35 the part 31 of the operating shaft 29 and by means of the rotation of the bevel gears 28, 27 and spur gears 21, 20, the lifting screw 16 is rotated clockwise and in its rotation acts upon the nut 15 to elevate the 40 ram 13.

This rotation of the shaft 22 in the direction of the arrow on Fig. 4, causes the pawls 36 to ride over the teeth of the ratchet without imparting any movement to the gear 34 45 and the pinion 38, worm gear 39, worm 40, gear 44, pinions 45, 48, 49 and brake wheel 51, the brake arms 53 at this time being in frictional contact with said wheel 51 and retaining all of these elements at rest.

50 When the load has been lifted, the operating mechanism may be removed from the shaft 29 if desired and the friction of the arms 53 on the wheel 51 will be sufficient to retain the load in elevated position due to 55 the ratio of the various gears between the one-way clutch mechanism 33, 36 and said brake disk 51.

When it is desired to lower the load the operator may release the brake arms 53 from 60 the wheel 51 to a greater or lesser extent as desired, by manipulating the operating handle 57 and turning the cam member 56 about its axis.

When the brake arms 53 are thus released 65 from the wheel 51 the load upon the head

14 will cause the ram 13 to move downwardly and this downwardly movement will cause the screw 16 to rotate contra-clockwise and the rotary movement will be transmitted through gear 20 and pinion 21 to the shaft 70 22 which will be rotated in a reverse direction, i. e., in a direction opposite to that indicated by the arrow on Fig. 4.

This reverse rotation of the shaft 22 will cause the teeth of ratchet wheel 33 to engage the pawls 36 and impart rotary movement to gear 34, pinion 38, worm gear 39, worm 40, gear 44, pinions 45, 48, 49 and brake wheel 51.

Owing to the reduction in gearing the 80 brake wheel 51 will be rotated at considerable speed if the brake arms 53 are wholly removed from contact therewith but if the brake arms are retained in frictional contact with said wheel the speed of lowering 85 may be easily regulated even under the heaviest load by simply increasing or decreasing the frictional contact between the arms and wheel as desired.

The pinion 38 is provided with a centrally 90 disposed cylindrical boss 60 having a bearing in the annex 25 and in axial alinement therewith is a cylindrical projection 61 positioned in a recess in the under face of the cover 62 secured to the annex 25.

The gear 44 and small gear or pinion 45 revolve in a chamber 63 in the annex 25 this chamber being closed by the cover plate 64.

The worm 40 has a steep-pitched thread so that it may be rotated by the worm gear 39.

100 It is believed that the operation and many advantages of the invention will be understood without further description.

Having thus described my invention, I 105 claim—

1. In a device of the class described, a standard; a ram reciprocable therein; a nut in said ram; a rotatable screw in said nut; a shaft parallel with said screw; intermeshing gearing between said shaft and screw; means for rotating said shaft to elevate the ram; a driving gear loosely mounted on said shaft; an over-running connection between said shaft and driving gear adapted to impart rotary movement to said driving gear 110 only during the lowering of the ram; and frictionally controlled mechanism actuated by said driving gear for retarding the speed of said ram.

2. In a device of the class described, a 120 standard; a ram reciprocable therein; a nut in said ram; a rotatable screw in said nut; a shaft parallel with said screw; intermeshing gearing between said shaft and screw; means for rotating said 125 shaft to elevate the ram; a driving gear loosely mounted on said shaft; an over-running connection between said shaft and driving gear adapted to impart rotary movement to said driving gear only during the 130

lowering of the ram; a brake wheel rotatable by said driving gear; brake arms normally contacting therewith and preventing the rotation thereof; and means for separating the arms from said wheel.

3. In a device of the class described, a standard; a ram reciprocable therein; a nut in said ram; a rotatable screw in said nut; a shaft parallel with said screw; intermeshing gearing between said shaft and screw; means for rotating said shaft to elevate the ram; a driving gear loosely mounted on said shaft; an over-running connection between said shaft and driving gear adapted 10 to impart rotary movement to said driving gear only during the lowering of the ram; a brake wheel rotatable by said driving gear; a brake arm; a spring for forcing said arm into contact with the brake wheel; and 15 means for separating said arm from said brake wheel.

4. In a device of the class described, a standard; a ram reciprocable therein; a nut in said ram; a rotatable screw in said nut; a shaft parallel with said screw; intermeshing gearing between said shaft and screw; means for rotating said shaft to elevate said shaft and screw; means for rotating said shaft to elevate the ram; a driving gear 20 loosely mounted on said shaft; an over-running connection between said shaft and driving gear adapted to impart rotary movement to said driving gear only during the lowering of the ram; a brake wheel rotatable by said driving gear; a brake arm; a spring for forcing said arm into contact with the brake wheel; and a cam for separating said arm from said brake wheel.

5. In a device of the class described, a standard; a ram reciprocable therein; a nut in said arm; a rotatable screw in said nut; a shaft parallel with said screw; intermeshing gearing between said shaft and screw; means for rotating said shaft to elevate the ram; a driving gear loosely mounted on said shaft; an over-running connection between said shaft and driving gear adapted to impart rotary movement to said driving gear only during the lowering of the ram; a brake wheel rotatable by said driving gear; a brake arm; a spring for forcing said arm into contact with the brake wheel; a cam for separating said arm from said brake wheel; and a manually actuated arm 55 to move said cam about its axis.

6. In a device of the class described, a standard; a ram reciprocable therein; a nut in said ram; a rotatable screw in said nut; a shaft parallel with said screw; intermeshing 60 gearing between said shaft and screw; means for rotating said shaft to elevate the ram; a driving gear loosely mounted on said shaft; an over-running connection between said shaft and driving gear adapted 65 to impart rotary movement to said driving

gear only during the lowering of the ram; a brake wheel; arms coacting therewith to normally prevent rotation thereof; means for separating said arms from contact with said wheel; and gearing between said driving gear and brake wheel.

7. In a device of the class described, a standard; a ram reciprocable therein; a nut in said ram; a rotatable screw in said nut; a shaft parallel with said screw; intermeshing 75 gearing between said shaft and screw; means for rotating said shaft to elevate the ram; a driving gear loosely mounted on said shaft; an over-running connection between said shaft and driving gear adapted to 80 impart rotary movement to said driving gear only during the lowering of the ram; a brake wheel; arms coacting therewith to normally prevent rotation thereof; means for separating said arms from contact with 85 said wheel; a worm wheel rotatable by said driving gear; a steep-pitched worm rotated by said worm gear; and a train of gears between said worm and brake wheel.

8. In a device of the class described, a standard; a ram reciprocable therein; a nut in said ram; a rotatable screw in said nut; a shaft parallel with said screw; intermeshing 90 gearing between said shaft and screw; means for rotating said shaft to elevate the ram; a driving gear loosely mounted on said shaft; an over-running connection between said shaft and driving gear adapted to 95 impart rotary movement to said driving gear only during the lowering of the ram; a brake wheel; arms coacting therewith to normally prevent rotation thereof; means for separating said arms from contact with 100 said wheel; a worm wheel rotatable by said driving gear; a steep-pitched worm rotated by said worm gear; a large gear secured to and revoluble with the worm shaft; a gear secured to and revoluble with the brake wheel; and two small gears rotatable together and meshing respectively with the 110 large gear and the brake wheel gear.

9. In a device of the class described, a standard; a ram reciprocable therein; a nut in said ram; a rotatable screw in said nut; a shaft parallel with said screw; intermeshing 115 gearing between said shaft and screw; means for rotating said shaft to elevate the ram; a driving gear loosely mounted on said shaft; an over-running connection between said shaft and driving gear adapted to 120 impart rotary movement to said driving gear only during the lowering of the ram; a brake wheel; arms coacting therewith to normally prevent rotation thereof; means for separating said arms from contact with 125 said wheel; a pinion rotatable by said driving gear; a worm wheel secured to and rotatable with said pinion; a worm meshing with said worm wheel; a worm shaft perpendicular to the axis of the lifting screws; 130

and gearing actuated by the rotation of said worm shaft to rotate said brake wheel.

10. In a device of the class described, a standard; a ram reciprocable relatively thereto; means for elevating said ram; a shaft parallel with said ram; intermeshing gearing between said shaft and elevating means; means for positively rotating said shaft in one direction to actuate said elevating means; a driving gear loosely mounted on said shaft; an over-running connection between said shaft and driving gear

adapted to impart rotary movement to said driving gear only during the lowering of the ram; and manually controlled mechanism actuated by said driving gear for retarding the speed of said ram. 15

Signed by me at 294 Washington St., Boston, Mass., this 25th day of October, 1921.

FRANK L. GORMLEY.
